UNITED STATES PATENT OFFICE.

JOHN LOUIS KUNKLE, OF MCCOYSVILLE, PENNSYLVANIA.

COW-TAIL HOLDER.

1,131,527.

Specification of Letters Patent.

Patented Mar. 9, 1915.

Application filed September 10, 1913. Serial No. 789,102.

To all whom it may concern:

Be it known that I, JOHN L. KUNKLE, a citizen of the United States, residing at McCoysville, in the county of Juniata and 5 State of Pennsylvania, have invented new and useful Improvements in Cow-Tail Holders, of which the following is a specification.

This invention relates to improvements in 10 cow tail holders and has particular reference to that class of devices wherein one end of the device is clamped around the tail and the opposite end to the hind leg of the animal, so as to prevent movement of the tail 15 during the operation of milking.

The primary object of the present invention is the provision of a device of the above mentioned character wherein the clamping jaws may be independently or simultaneously 20 moved to open position, and automatically locked when moved to closed position.

Another object of the invention is the provision of a reversible holder, either end 25 of which may be clamped around the tail or to the leg of the animal, thus facilitating the application of the device.

A further object of the invention is the provision of a device of the class in question which is simple in construction, cheaply 30 manufactured and positive in its operation.

With these and other objects in view which will appear as the nature of the invention is better understood, the invention 35 consists in the specific construction and combination of parts hereinafter more fully described and particularly pointed out in the appended claims.

In the drawing forming a portion of this 40 specification and in which like numerals of reference indicate similar parts in the several views: Figure 1 is a perspective view of the device showing the jaws partly opened. Fig. 2 is a top edge view showing 45 the jaws locked in closed position. Fig. 3 is a detail perspective view of one of the jaws. Fig. 4 is a detail perspective view of the main body portion of the device. Fig. 5 is a view showing the lower stationary 50 jaws in section and the upper jaws in elevation. Fig. 6 is a sectional view taken on

line 4—4 of Fig. 2. Fig. 7 is a similar view showing the manner of moving the upper jaws out of engagement with each other to permit of their opening.

55

Referring to the drawing by numerals, 1 indicates the main body portion of the device, which is constructed from any suitable yieldable material preferably resilient metal for the purpose which will hereinafter be 60 described. The lower rail 2 of the frame is longitudinally slotted as at 3 for the major portion of its length, and terminates in forwardly curved portions forming stationary jaws 4 which coöperate with the movable 65 jaws 5. Rising centrally from the opposite sides of the rail 2 and formed integrally therewith are spaced pivot ears 6 and 7 between which the movable jaws 5 are pivoted. The opposite side edges of the ears are 70 formed with shoulders 8 to provide a stop for limiting the movement of said movable jaws in one direction in a manner herein-after more fully described.

The movable jaws 5 have their free ends 75 curved downwardly for engagement with the stationary jaws 4, and are integrally connected with pivot lugs 10 which extend rearwardly of and downwardly from said jaws and arranged in overlapping engagement 80 between the pivot ears 6 and 7. The outer side of each lug 10 is formed adjacent its upper edge with a stud 11 by means of which the jaws 5 are mounted in an opening 12 in the ears 6 and 7 for pivotal movement. 85 The inner surface of each of the lugs are formed with oppositely disposed locking shoulders 13 and 13' adapted for locking engagement with each other for the purpose of retaining the said movable jaws 5 locked 90 in closed position. By reason of the fact that the said ears 6 and 7 are constructed from resilient material, the shoulders 13 and 13' are normally held in locking engagement by the inherent yieldableness of 95 the said ears, or in other words the tendency of the upper portion of the ears to approach each other. The pivot lugs 10 are tapered downwardly so that the lower portions thereof are normally spaced to provide 100 a leverage whereby the said portions are adapted to be moved toward each other.

thus forcing the upper portion and the locking shoulders 13 and 13' outwardly and out of engagement with each other against the tension of the said ears to permit the jaws 5 to be independently or simultaneously moved to open position, the said jaws as is obvious being also held in open position under tension of the said ears 6 and 7. The lower edge of the said ears are cut away as 10 at 14 to permit the lower portions of the lugs 10 to be engaged by the thumb and finger of the operator whereby the necessary inward pressure may be applied to the lugs to permit opening of the jaws as hereinabove described. The said jaws 5 at their point of juncture with the lug 10 are formed with shoulders 15 the lower edges of which are adapted to engage the shoulder 8 to limit the closing movement of the jaws.

20 From the foregoing description taken in connection with the accompanying drawing it will be manifest that I have provided a device of the class in question, by reason of the fact that it is reversible and may be 25 easily and quickly applied to the animal and automatically locked in position thereon. And while I have herein illustrated the preferred form of my invention, it is to be understood that I am not to be limited to the 30 precise structure herein shown and described as various changes may be made within the scope of the appended claims.

What I claim is:—

1. A reversible cow tail holder comprising a frame formed with oppositely disposed stationary jaws, a pair of jaws pivoted in said frame and movable toward and away from said stationary jaws, and means formed on said movable jaws and coöperating to simultaneously lock said jaws in closed position.
2. A cow tail holder comprising a frame having oppositely disposed stationary jaws and spaced resilient ears, a pair of oppositely movable jaws pivoted between said ears, means for opening said jaws against tension of the ears, and means for automatically locking said jaws under the tension of the ears.
3. A cow tail holder comprising a frame having oppositely disposed stationary jaws and spaced resilient ears, a pair of oppositely movable coöperating jaws pivoted between said ears, means formed on said movable jaws for moving the latter to open position against the tension of said ears and locking means on the first mentioned means for retaining said jaws closed under the tension of said ears.
4. A cow tail holder comprising a frame formed with oppositely disposed stationary jaws and spaced resilient upstanding ears disposed between said jaws, a pair of coöperating movable jaws pivoted between said ears, and means for automatically locking

said movable jaws closed under the tension of said ears.

5. A cow tail holder comprising a frame formed with oppositely disposed stationary jaws and spaced resilient upstanding ears disposed between said jaws, a pair of movable jaws having pivot lugs arranged in overlapping engagement and pivoted between said ears, and means formed on said lugs for automatically locking said jaws closed under tension of said ears.

6. A cow tail holder comprising a frame formed with oppositely disposed stationary jaws and spaced resilient upstanding ears disposed between said jaws, a pair of movable jaws having pivot lugs arranged in overlapping engagement and pivoted between said ears, means formed on said lugs for automatically locking said jaws closed under tension of the ears, and said lugs providing means for releasing said locking means.

7. A cow tail holder comprising a frame formed with oppositely disposed stationary jaws and spaced resilient upstanding ears disposed between said jaws, a pair of movable jaws having pivot lugs arranged in overlapping engagement and pivoted between said ears, the adjacent faces of said lugs being formed with shoulders for locking engagement when the jaws are closed, said ears retaining said shoulders operatively associated, and means for moving the shoulders out of engagement against the tension of said ears.

8. A cow tail holder comprising a frame formed with oppositely disposed stationary jaws and spaced upstanding ears disposed between said jaws, a pair of movable jaws pivoted between said ears, and the opposite edges of said ears being provided with shoulders for engagement with said movable jaws in closed position.

9. A cow tail holder comprising a frame having oppositely disposed stationary jaws and spaced upstanding ears arranged between said jaws, movable jaws formed with pivot lugs pivoted between said ears, the adjacent faces of said lugs being formed with shoulders for locking engagement when the jaws are closed, said ears retaining said shoulders operatively associated, and the lower portion of said lugs being spaced and adapted to be moved toward each other for moving the shoulders out of engagement against the tension of said ears as described.

10. A cow tail holder comprising a resilient frame formed with oppositely disposed stationary jaws, a pair of coöperating movable jaws having pivot lugs pivoted in said frame, said jaws being held in closed position under the tension of said frame, and said lugs providing means for opening said jaws against the tension of said frame.

11. A cow tail holder comprising a re-

silient frame formed with oppositely disposed stationary jaws, a pair of coöperating movable jaws having pivot lugs pivoted in said frame and arranged in overlapping engagement, said jaws being held closed under the tension of the frame and said lugs having their lower portions normally spaced and adapted to be moved toward each other

against the tension of said frame to permit said jaws to be moved to open position. 10

In testimony whereof I affix my signature in presence of two witnesses.

JOHN LOUIS KUNKLE.
